UNITED STATES PATENT OFFICE

JAMES M. SWAN, OF INDIANAPOLIS, INDIANA, ASSIGNOR TO SENTINAL PRINTING COMPANY, OF INDIANAPOLIS, INDIANA, A CORPORATION

COMBINATION DISPLAY AND INFORMATION BOOK

Application filed April 18, 1931. Serial No. 531,159.

This invention relates to a combination display and information book, and more particularly a record of accounts book embodying statistical information associated with a calendar or other feature displays.

The principal object of the invention is to provide an article of the above character wherein one of the two covers of the book portion can be used as a hanger adapted to 10 hang the article for display upon a wall, the calendar or the like being mounted upon the other cover of the book portion so as to be supported thereby in display position, while permitting the removal of the article from 15 the wall for the purpose of making entries in the book portion or consulting the statistical information contained therein.

Another feature of the invention resides in the construction of the article, whereby 20 upon removal of the display portion mounted upon the cover, the book may be permanently removed from the wall or filed away with the records contained thereon.

More particularly the invention applies to 25 a calendar comprising a sheet for each month which is removably secured to one backing of the book portion, the other backing having printed on the exterior thereof a display advertisement or the like, so that when the 30 same is hung upon the wall, the display advertisement and calendar will be exposed and when removed from the wall, the entry and information sheets contained between the covers may be used or consulted. Upon the 35 monthly calendar sheets being completely removed at the end of the year, the book with the cover thereon remains for continued use or filing away as a permanent record.

The full nature of the invention will be 40 understood from the accompanying drawings and the following description and claims:

In the drawings, Fig. 1 is a perspective view of the book in closed position with the calendar mounted thereon. Fig. 2 is the 45 same as Fig. 1, showing the display cover and calendar in extended position mounted upon the wall. Fig. 3 is a perspective view showing the book portion in normal position after the calendar has been removed therefrom for 50 further use or filing.

In the drawings there is shown a book comprising covers 10 and 11 for embracing pages 12 suitably printed for receiving entries and for imparting statistical information. The pages 12 are secured to the covers 10 and 11 by the staples 13 in the usual manner. Pasted, stitched or otherwise secured to the outside of the cover 11 there is a twelve-sheet calendar 14, one sheet to each month, said sheets being stitched together in the usual manner by the stitching 15.

When it is desired to employ the article as a display calendar, the cover 10 is turned upwardly so as to extend in alignment with the integral cover 11, as shown in Fig. 2. In 65 this position the display cover 10 is provided with perforations 16 for mounting by a suitable support on a wall or the like. In this position the display and calendar are exposed in the usual manner. When it is desired to make an entry in the book, or consult 70 the information contained therein, it is removable from the wall and utilized as a book in the ordinary manner.

Inasmuch as the monthly sheets of the calendar will be removed at the end of the respective months, they will all have been removed from the cover 11 at the end of the year. Thus, the record and information book will remain free from the calendar in 80 the form of an ordinary book of this character for continued use or for filing away as a permanent record of the preceding year.

The invention claimed is:

1. An article of the character described, comprising a plurality of data pages, a pair of cover sheets embracing said pages and permanently secured thereto, a plurality of display sheets secured to the exterior of one of said covers and display matter on the other cover, said last-mentioned cover being provided with means for hanging the same in extended alignment with the first-mentioned cover to provide a hanging support for the display sheets.
2. An article of the character described, comprising a book cover normally folded upon itself in book formation, a plurality of data pages contained therein and permanently secured thereto, and a plurality of display

sheets removably secured to the exterior of one side of said cover, the other side of said cover being adapted to extend upwardly for suspending the said sheets in display position, and downwardly to embrace said pages in non-display position.

3. An article of the character described, comprising a plurality of calendar sheets arranged for successive exposure by the removal of the preceding sheet, a plurality of information pages arranged for data reception, and a cover sheet adapted to provide a display and hanging support for the calendar sheets when in one position and a cover for the pages when in another position, the calendar sheets being secured for removal from said cover sheet, and said pages being permanently secured thereto.

In witness whereof I have hereunto affixed
20 my signature.

JAMES M. SWAN.
